UNITED STATES PATENT OFFICE.

ROLLETTA RAPPEL, OF REEDSVILLE, WISCONSIN.

CONVERTIBLE CHAIR.

1,150,622.

Specification of Letters Patent. Patented Aug. 17, 1915.

Application filed April 2, 1914. Serial No. 829,072.

To all whom it may concern:

Be it known that I, ROLLETTA RAPPEL, a citizen of the United States, residing at Reedsville, in the county of Manitowoc and State of Wisconsin, have invented certain new and useful Improvements in Convertible Chairs; and I do hereby declare the following to be a full, clear, and exact description of the invention, such as will enable others skilled in the art to which it appertains to make and use the same.

This invention relates to chairs, and has for its object to provide a chair having a hollow body adjustably supporting a seat.

With this and other objects in view, the invention consists in the novel construction, arrangement and formation of parts as will be hereinafter specifically described, claimed and illustrated in the accompanying drawings, in which,

Figure 1 represents a front elevation of the chair, Fig. 2 represents a front elevation thereof, showing the extensible ends of the seat in raised position and the door of the cabinet bottom open, Fig. 3 represents a vertical transverse sectional view through the chair, and, Fig. 4 represents a rear elevation of the chair, showing the seat in raised position.

Referring to the drawing in detail, where-in similar reference numerals designate corresponding parts throughout the several views, the numeral 5 indicates the body of the chair which is preferably of rectangular formation and hollow, comprising four vertical walls and a bottom 6. The front wall of the body is formed with an opening adapted to be closed by a door 7 provided with a suitable knob 8 and supported on hinges 9. Within the lower portion of the body 5 one or more shelves are secured.

A foot rest 11 is secured adjacent the bottom of the rear wall of the body and is adapted to support the feet of the occupant of the chair.

The upper end of the body 5 is open, and the inner faces of the opposite walls thereof are formed with a plurality of horizontally disposed ledges or teeth 12. The seat 13 of the chair is disposed above the body 5 and is adapted to rest upon the top edges of the walls of the latter when in its lower position.

Supporting members 14 are pivotally secured adjacent the center of the under side of the seat 13 by hinges 15, and the lower

ends of said members are normally held in spaced relation and against the side walls of the body 5 by a spring 16. When the seat 13 is moved upwardly, the lower edges of the supporting members 14 ride over the inclined faces of the teeth 12 and automatically spring out by the action of the spring 16 over the teeth to lock the seat at any desired height. Lugs 17 are formed at the lower edges of the supporting members 14 and are adapted to engage strips 18 secured to the inner faces of the side walls of the body to prevent the members 14 from being accidentally withdrawn from the body 5.

A cord or the like 18^a is secured adjacent the lower end of each supporting member 14, and is extended through an opening in the other supporting member and through suitable openings formed in the seat 13. The upper ends of the cords are formed with eyes 19 or other suitable means to prevent the ends from slipping through the openings in the seat 13. The string or cords 18^a are adapted to be pulled upwardly to draw the supporting members 14 together against the tension of the spring 16 to release them from engagement with the teeth 12 whereby the seat 13 may be lowered.

The opposite ends of the seat 13 are pivotally connected by hinges or the like with extensible end members 20 adapted to be supported in horizontal position by bracing arms 21 pivoted at 22 to the under sides of said ends and adapted to engage lugs 23 formed on the outer faces of the sides of the body. In Fig. 2 the end members are shown extended, and in this position the top of the chair is large enough to support wash-tubs, ironing boards or similar articles of the laundry or kitchen.

What I claim is:

A chair comprising a hollow body having an open upper end, a plurality of horizontally disposed ledges secured to the inner faces of the walls of said body, a seat disposed over said open end, supporting members hinged to the under side of said seat in the central portion thereof, a coil spring having its ends secured to the supporting members for normally holding said members in extended position in engagement with said ledges, said seat having a pair of apertures therein positioned at opposite points and adjacent the opposite edges of said seat, each of said supporting members having an aperture therein, a pair of flexible

members, one of said members having one of its ends secured to one of the supporting members and the other flexible member having one of its ends secured to the other supporting member, said flexible members then passing through the apertures in the supporting member opposite, the free ends of said flexible members extending upward through the apertures in said seat, and 10 means to prevent said free ends of the flexible members from slipping through said

apertures whereby said supporting members can be released from engagement with said ledges when the terminal ends of said flexible members are pulled upwardly.

15

In testimony whereof I affix my signature in presence of two witnesses.

ROLLETTA RAPPEL.
